UNITED STATES PATENT OFFICE

2,664,961

ADJUSTABLE BLADE FAN

Charles F. Goede, New Philadelphia, Ohio, assignor to Joy Manufacturing Company, a corporation of Pennsylvania

Application October 24, 1947, Serial No. 781,909

13 Claims. (Cl. 170—160.6)

1

My invention relates to adjustable blade fans, and more particularly to adjustable blade fans of the vane axial type.

It is customary in the designing of adjustable blade fans to choose a size of motor adequate for the drive at the maximum pitch angle which it is intended they shall have. It has been found in practice, however, that the users of these fans are not always satisfied to employ them for the moving of the volume of air for which they were designed, and will readjust the fan blades to such angles that the motor may be seriously overloaded. It would therefore be highly advantageous if suitable means could be provided which would prevent adjustment of the fan blades to positions which would require more power than their associated motors were designed to provide, especially if such adjustment limiting means could be made such as to be inaccessible to any tampering without substantial trouble being involved, and especially also if such means could be of such a nature that it might be incorporated in whole series of blades and by mere variation in finishing steps take care of differential capacities.

It is an object of my invention to provide an improved adjustable blade fan. It is another object of my invention to provide an improved adjustable blade fan of the vane axial type. It is a further object of my invention to provide an adjustable blade fan having improved blade supporting and rotating means. It is still another object of my invention to provide an improved adjustable blade fan having incorporated therein means for precluding improvident adjustment of the pitch angle of the blades in such a manner as to result in an overloading of the fan driving motor. It is yet a further object of my invention to provide an improved adjustable blade fan having incorporated therein improved means for controlling the maximum pitch angle of the blades and adapted to permit a single blade blank to be employed in the production of fans of substantially different output, merely by variation in the finishing operations. It is still another object of my invention to provide an improved blade angle adjustment limiting means which while wholly effective shall be out of harm's way, and not subject to alteration without deliberate disassembly of parts so that

2

such adjustment limiting means can be reached. Other objects and advantages of the invention will, however, hereinafter more fully appear.

In the accompanying drawings, in which one form in which my invention may be embodied is shown for purposes of illustration,

Fig. 1 is an end view of a vane axial fan in which my invention is incorporated, with a portion broken away.

10 Fig. 2 is a section on the plane of the line 2—2 of Fig. 1, on an enlarged scale.

Fig. 3 is a detail section on the plane of the line 3—3 of Fig. 1, on an enlarged scale.

15 Fig. 4 is a section on the plane of the line 4—4 of Fig. 3, with parts broken away.

Fig. 5 is a fragmentary sectional view on the plane of the line 5—5 of Fig. 3.

20 Fig. 6 is an enlarged perspective view showing a portion of a fan blade and the whole of the hub and pivot element thereof.

Fig. 7 is a view similar to Fig. 4 showing parts in a different adjusted position.

Fig. 8 is a view similar to Fig. 4 showing the parts in still a different adjusted position.

25 Fig. 9 is a perspective view showing a portion of a blade and a portion of the blade supporting rotor construction, with parts broken away, to illustrate details of the invention, the view being on a different scale.

30 Referring to the drawings, and first to Figs. 1 and 2; it will be observed that a fan and motor casing C is made up of a deflector ring 1, desirably in the form of an aluminum spinning, a ring 2 forming a fan housing, and a ring or outer casing 3 having stationary vanes 4 permanently secured thereto and connected at their inner edges with an inner ring member 5 to which the vanes are also secured and which in turn is fixedly secured to and supports a motor positioning plate 6 having an opening 7 therethrough. A motor 8, of a horsepower suited to the

35 designed air displacement of the fan, is provided with a motor shaft 9 and is secured as by studs 10 and nuts 11 to the supporting plate 6, being positioned with respect to said plate, transversely, by means of a surface of rotation 12 on the motor casing cooperating with an internal surface of rotation 13 formed on the plate 6, and longitudinally, by means of a plane transverse surface 14 cooperating with an opposite plane surface 15 on

the motor positioning plate 6. The motor shaft 9 carries a blade carrying rotor 16, desirably of light metal such as aluminum, having the hub 17 thereof provided with a steel bushing or insert 18 secured by appropriate holding means 19 to the shaft 9. The rotor includes a web portion 20 to which a rim portion 21 is integrally secured. The rim portion is provided with a peripheral surface 22, which corresponds to a portion of a spherical surface. The rim portion 21 has at various equally-spaced positions about it thickened portions 23 in which sockets for the reception of the hub and shaft portions of the fan blades are formed. Associated with the rotor 16 at each of the portions 23 is a fan blade 25 consisting of an appropriately formed blade portion 26, desirably made of aluminum or other light material, a tapering hub portion 27, and a pivot element 28, said tapering hub portion being in the form of a solid of revolution of which the axis lies in the same line with the axis of the pivot element 28 and said pivot element comprising a pair of collar or shoulder portions 29 and 30 connected by a reduced portion 31, said collar portions appropriately peripherally formed, as by knurling, so that when cast in position in the fan blade 25 they will resist tendencies to loosen their connection with the blade, the spool-like construction preventing the blade from pulling axially away from the pivot element 28 and the knurling, or the like, preventing relative rotation between element and blade. The pivot element 28 has a cylindrical portion 33 which is adapted to be rotatably received within a tubular insert or sleeve 34, desirably made of steel and connected securely to the rotor rim as by the casting of the metal of the rotor around it, one such bearing sleeve in each of the thickened portions 23. These sleeve portions may be knurled on end collar portions 35 so as to hold them non-rotatively relative to the rotor. The inner ends of the blades are formed with surfaces 37 which are struck on arcs of radii only slightly exceeding the radius of the spherical surface 22. The hub portions 27 have peripheral surfaces which are, in the main, surfaces of revolution, and the portions 23 have sockets 40 which correspond closely to the peripheral contour of the hub portions 27. Since each hub portion and associated pivot element has a maximum diametric dimension in each plane to which their axes are perpendicular at least as great as in any parallel planes nearer the inner end of said pivot element, the blades are positionable in fully assembled relation with the rotor by movement axially of the tapering sockets in the rotor. With the portions of the hub portions 27 within which the pivot elements 28 are fixed inside the sockets 40 there is not only a very compact construction, but one in which the possibility of breaking of the blades loose from the pivots is much reduced. Blade angle fixing screws 41 extend through threaded openings 42 formed in the material of the rotor surrounding the socket member 34 and through the wall of this socket member. The wall of the socket 40 is provided with an arcuate recess 43, and, as originally cast or molded, the hub portions 27 have projecting portions 44 which may be of such arcuate dimension as to occupy any desired portion of the arcuate dimension of the recesses 43 and as originally cast will usually have such angular extent as, if inserted in said arcuate recesses, to limit the potential turn of the blades to not more than the minimum useful

amount. By appropriately milling away the material of the projections 44, these projections may be caused to limit the angular adjustment of the fan blades about the axes of the pivots 33 to any desired extent. For example, if a small angle of adjustment is desired, the width arcuately of the portions 44 may be a relatively large portion of the arcuate extent of the recesses 43. If a relatively large range of angular adjustment of the blade is desired, the width arcuately of the portions 44 may be substantially reduced, and the difference in the arcuate extent of these portions and of the recesses in which they are received will definitely determine the range of angular adjustment of the blades.

The projections will be so located with respect to the blades, or the recesses 43 will be so located with respect to the sockets—or there may be such location both of the projecting portions with respect to the blade and of the recesses with respect to the socket—as to determine the desired angular relation of the parts in both minimum and maximum pitch angle position.

The outer surface of the hub 27 alongside the blade may be marked with graduations to cooperate with an index line on the peripheral surface of the rotor to indicate the actual angular relation of the blades to the rotor. For example, Fig. 8 shows a fan blade positioned in minimum pitch angle position; Fig. 7 the maximum angular position possible between the parts with the construction shown; and Fig. 4 shows an intermediate position of adjustment.

It will be noted that the rotor is fitted with a nose 45 which may be of spun aluminum, and suitably rounded or domed to direct or guide the air flow and this nose may be held in position by flexible spring latch elements 46 secured at radially extending portions 47 thereof to the web 20 of the fan rotor.

It will be noted moreover that sole reliance is not placed on the angle fixing screws 41 to hold the fan blades in adjusted position, and that lock washers 48 and lock nuts 49 are arranged on the threaded extremities 50 of the elements 28 and, acting against the end 51 of the sleeve 34, draw the collar 30 tightly against the upper end of the sleeve 34.

Suitable fixtures may be used for setting the fan blades, and when one blade is set at the desired angle, and the screw 41 and the nut 49 are tightened, a ring having studs spaced equally with the blade spacing may be fixed coaxially with the fan rotor with one of its studs in contact with the fixed (set) blade. The other blades may then be moved to like contact with other studs (their respective ones) and fixed by the screw and by the nut, associated with them, and thus like settings for all the blades will be effected.

From the foregoing description it will be obvious that I have provided an improved, simple and effective blade angle control and a correspondingly improved fan rotor construction. The lugs may all be made the same size on original blade castings of a given size, and machined (milled) to proper angular dimension. Then with the recess cast in the socket wall in the rotor—so that it constitutes an enlargement of the bore or socket at one side of the latter, a very simple method of producing these recesses is provided, recesses with end walls extending radially from the axis of the socket. By reason of the housed in location of the limit means an improved result in security against accidental destruction of these means is provided. The

same blade blanks, so to speak, can be made up for use in fans of different volume and pressure characteristics; and each fan, in which the lug width, or more strictly the angular relation of the lug edges to the associated blade, is the same for all blades will be adapted not only for like normal settings, but for like extreme settings. Obviously by forming the taper of the hub 27 with an arcuate generatrix, the selection of a milling cutter of corresponding radius will make very easy the cutting of the projection 44 to any desired width. The resultant form of the principal surface of the hub will be a surface of revolution having its generatrix arcuate and with its concavity facing away from the axis of the surface. And it may be noted that the lug 44 projecting from the surface of the hub portion has the surfaces at its opposite sides in planes intersecting along the axis of the hub (see Fig. 4). It will further be noted that the radial sockets in the rim portion 24 have circular mouths opening through the outer periphery of the rim and have sidewalls principally in the form of a surface of revolution which tapers in the direction of the center of the rotor element. The fan blades also have hub portions provided with a tapering sidewall principally in the form of a surface of revolution mating with the first mentioned surface of revolution. The means for limiting turning of the hub portions in the sockets includes, for each blade and socket, a recess in the tapering socket wall and a projection from the mating wall, said recesses having a radially outer wall nearer the axis of said surfaces of revolution than the length of the radius of said circular mouths and said projections each having an outer wall adjacent, when said blades are assembled on said rotor element, the radial outer wall of the recess and said walls having the elements thereof mutually parallel and parallel to the axis of said surface of revolution. Were it desired to recess the peripheral wall of the hub portion 27 and extend into the recess a projection of predetermined angular width, to reverse the relative positions of the limit means, this would be within the broadest aspect of my invention. Also, if desired, in lieu of the single stop lug, spaced lugs in separate recesses, or in an elongated recess, may be employed. The stop, also, may be formed on other portions of the pivot structure for the blades, such as between the pivot element and its bearing.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A fan rotor element for an axial flow fan comprising a hub, a web, a rim having radial sockets therein having mouths opening outwardly through said rim, and including bearing inserts cast in said rim and disposed radially inwardly of the mouths of said sockets, fan blades each having a pivot element cast in its inner end, said pivot elements each having a portion received and journaled in one of said bearing inserts and having its portion which is cast in a fan blade lying entirely radially inwardly of the mouth of the socket but outwardly of the bearing insert, and the portions of the inner ends of

said fan blades in which said pivot elements are cast closely received in said radial sockets, and means for holding said pivot elements in said sockets.

5. 2. A fan rotor element for an axial flow fan comprising a hub, a web, a rim having radial sockets therein having mouths opening outwardly through said rim, and including bearing inserts cast in said rim and spaced radially inwardward from the mouths of said sockets, fan blades each having a pivot element cast in its inner end, said blades each having the entire portion thereof circumferentially surrounding its associated pivot element received in one of said sockets, and having its associated pivot element received and journaled in one of said bearing inserts, and means for holding said pivot elements in said sockets, and for maintaining said blades each in the same angular relation to a plane which includes the axis of its socket and the axis of the rotor, said blades and said rim having blade angle-limiting stop surfaces located wholly radially inward of the mouth of each socket and radially outward of its bearing insert.
10. 3. A fan blade including a blade portion, a hub portion adapted for reception in a socket and of greater diameter than the thickness of said blade portion at the portion of the latter closest to said hub portion and tapering away from said hub portion, and a pivot element cast in position in said hub portion, said hub portion of greater length than the length of the portion of said pivot element that is cast therein and having the part thereof in which said pivot element is cast at least principally in the form of a tapering solid of revolution of which the axis lies in the same line as the axis of said pivot element.
15. 4. A fan blade including a blade portion, a hub portion adapted for reception in a socket and of greater diameter than the thickness of said blade portion at the portion of the latter closest to said hub portion and tapering away from said hub portion, and a pivot element cast in position in said hub portion, said hub portion having the part thereof in which said pivot element is cast at least principally in the form of a tapering solid of revolution of which the axis lies in the same line as the axis of said pivot element.
20. 5. An adjustable blade fan comprising a rotor having tapering sockets opening inwardly from mouths in the periphery of said rotor and having radial bores for the reception of fan blade pivot elements, said radial bores communicating with said tapering sockets, fan blades having hub portions filling at least the mouths of said sockets and pivot elements received in said bores when said blades are assembled on said rotor, each hub portion and associated pivot element having a maximum diametric dimension in each plane to which their axes are perpendicular at least as great as in any parallel planes nearer the inner end of said pivot element whereby said blades are positionable in assembled relation with said rotor by movement axially of said sockets, and means located wholly between the periphery of said rotor and the radially outer ends of said bores for limiting the angular adjustment of said blades.
25. 6. An adjustable blade fan comprising a rotor having tapering sockets opening inwardly from mouths in the periphery of said rotor and having

radial bores for the reception of fan blade pivot elements, said radial bores communicating with said tapering sockets, fan blades having hub portions filling at least the mouths of said sockets and pivot elements received in said bores when said blades are assembled on said rotor, each hub portion and associated pivot element having a maximum diametric dimension in each plane to which their axes are perpendicular at least as great as in any parallel planes nearer the inner end of said pivot element whereby said blades are positionable in assembled relation with said rotor by movement axially of said sockets, and means between the periphery of said rotor and the radially outer ends of said bores and enclosed wholly within the metal of said rotor for limiting the angular adjustment of said blades.

7. An adjustable blade fan comprising a rotor having tapering sockets opening inwardly from mouths in the periphery of said rotor and communicating with radial bores for the reception of fan blade pivots, fan blades having hub portions filling at least the mouths of said sockets and pivot elements received in said bores when said blades are assembled on said rotor, each hub portion and associated pivot element having a maximum diametric dimension in each plane to which their axes are perpendicular at least as great as in any parallel planes nearer the inner end of said pivot element whereby said blades are positionable in assembled relation with said rotor by movement axially of said sockets, and means between the periphery of said rotor and the radially outer ends of said bores for limiting the angular adjustment of said blades, said last mentioned means including a radial projection integrally formed on each of said hub portions and a recess for receiving said projection formed between the ends of the associated tapering socket.

8. An adjustable blade fan comprising a rotor having tapering sockets opening inwardly from mouths in the periphery of said rotor and communicating with radial bores for the reception of fan blade pivots, fan blades having hub portions filling at least the mouths of said sockets and pivot elements received in said bores when said blades are assembled on said rotor, each hub portion and associated pivot element having a maximum diametric dimension in each plane to which their axes are perpendicular at least as great as in any parallel planes nearer the inner end of said pivot element whereby said blades are positionable in fully assembled relation with said rotor by movement axially of said sockets, and means between the periphery of said rotor and the radially outer ends of said bores and enclosed wholly within the metal of said rotor for limiting the angular adjustment of said blades, said last mentioned means including a radial projection integrally formed on each of said hub portions.

9. An adjustable blade fan comprising a rotor having portions in which there are tapering sockets opening inwardly from mouths in the periphery of said rotor and communicating with radial bores for the reception of fan blade pivots, fan blades having hub portions filling at least the mouths of said sockets and pivot elements received in said bores, and means between the periphery of said rotor and the radially outer ends of said bores and enclosed wholly within the metal of said rotor for limiting the angular adjustment of said blades, said means including pairs of cooperating radially extending projections and recesses, a pair individual to each blade, such projection and recess for each blade carried one by

one of said portions and the other by the other of said portions and disposed, when said blade pivot is in the bore which receives it, in a common zone transverse to the axis of the hub of such blade, and having such relation to each other establishable by the insertion of the hub portion of the blade axially into its respective socket.

10. In an adjustable blade fan, a cast rotor comprising a hub, a web, and a peripheral flange portion having sockets therein tapering inwardly to open into bearing bores, fan blades having hub portions tapering correspondingly with said sockets and carrying pivot elements receivable in said bearing bores, set screws relative to which said blades are rotatable on their pivots while remaining stationary as to axial movement, for fixing the angles of the blades relative to said rotor, threaded clamping means respectively formed on and carried by said pivot elements for providing security of said blades after setting, and means including a recess and a projection between the inner and outer ends of said tapering sockets for limiting the maximum angular adjustment of said blades.

11. A fan rotor element having a rim portion having radial sockets having circular mouths opening through the outer periphery of said rim and having sidewalls principally in the form of a surface of revolution which tapers in the direction of the center of the rotor element, fan blades each having a hub portion having a tapering sidewall principally in the form of a surface of revolution mating with said first mentioned surface of revolution, and means for limiting turning of said hub portions in said sockets including for each blade and socket a recess in the tapering socket wall and a projection from said mating wall, said recesses each having a radially outer wall nearer the axes of said surfaces of revolution than the length of the radius of said circular mouths, and said projections each having an outer wall adjacent, when said blades are assembled on said rotor element, the radially outer wall of said recess, and said walls having the elements thereof mutually parallel.

12. A fan rotor element having a rim portion having radial sockets having circular mouths opening through the outer periphery of said rim and having sidewalls principally in the form of a surface of revolution which tapers in the direction of the center of the rotor element, fan blades each having a hub portion having a tapering sidewall principally in the form of a surface of revolution mating with said first mentioned surface of revolution, and means for limiting turning of said hub portions in said sockets including for each blade and socket a recess in the tapering socket wall and a projection from said mating wall, said recess having a radially outer wall nearer the axes of said surfaces of revolution than the length of the radius of said circular mouths, and said projections each having an outer wall adjacent, when said blades are assembled on said rotor element, the radially outer wall of said recess, and said walls having the elements thereof mutually parallel and parallel to the axis of said surfaces of revolution.

13. A fan blade having a hub portion having the periphery thereof in the form of a surface of revolution having its generatrix arcuate and with its concavity facing away from the axis of said surface, said hub portion having projecting from said surface of revolution a lug having surfaces

at its opposite ends lying in planes intersecting along the axis of said hub.
